UNITED STATES PATENT OFFICE.

HENRY CLARKE, OF BALTIMORE, MARYLAND.

SEAL-LOCK.

SPECIFICATION forming part of Letters Patent No. 249,457, dated November 15, 1881.

Application filed September 7, 1881. (Model.)

To all whom it may concern:

Be it known that I, HENRY CLARKE, a citizen of the United States, residing at Baltimore, in the county of Baltimore and State of Maryland, have invented new and useful Improvements in Seal-Catches, of which the following is a specification.

My invention relates to certain new and useful improvements in devices for securing doors of bonded or sealed cars, warehouses, &c. It has for its object simplicity in construction and absolute certainty of operation.

Prior to my invention very many improvements have been made in locks and seals for securing goods in bond. The locks have necessarily involved keys or intricate mechanism of some kind or other, and the seals involve also very many varied devices, the purpose of all being to provide against the opening of the door without the opening of the lock or the destruction of the seal.

My invention consists of a metallic seal-catch having a longitudinally-reciprocating bolt provided with an opening to receive the seal, and held in position by a spring-pawl concealed within the case, as will be herein-after and in detail explained.

In order that those skilled may know how to make and use my invention, I will proceed to describe the same, referring by letters to the accompanying drawings, in which—

Figure 1 is an elevation of a car or warehouse with my improved seal-catch secured thereto. Fig. 2 is a section of the seal-catch, taken at the line *x* *x*, Fig. 1. Fig. 3 is a horizontal section at the line *y* *y*, Fig. 2; Fig. 4, a bottom perspective view of the sliding bolt.

Similar letters indicate like parts in the several figures.

40 A B represent a cast-metal case composed of two parts, the base A being provided with suitable bolt-holes, *a*, at any desired point, for securing the same to a door or door-jamb. At the front projects upwardly a staple, C, having a slot, *b*, adapted to receive the end of the sliding bolt, as clearly shown at Fig. 3.

D is a raised projection to support the bolt and guide it in its movement.

E is a seat or bearing adapted to support and pivot a dog, F, which is returned to its normal position by a spring, G, one end of

which is secured to a lateral projection, *c*, on the dog F, and the other to a stud, *d*, projecting from the base-plate A.

B is a cap-plate or cover, which is secured 55 to the base-plate A by rivets or screws *e* *e*, which are concealed or covered in any permanent manner; or the cap-plate may be secured in any other manner thought desirable. The front end of the plate B has an opening in it 60 of such shape as to permit the reciprocation of the bolt H, which is preferably of the T form shown, so that it will not lift out of its seat in the projection C on the front end of the plate A. The upper or rib side of the bolt 65 is provided with a longitudinal opening, *f*, to receive the seal, as shown at Fig. 2, and the particular form and advantages of which are fully described in an application for Letters Patent which I am about to make. Leading 70 into this slot *f* is a gateway, *g*, which, when the bolt is in position to secure the seal, is concealed within the case or cap-plate B, as will be hereinafter explained.

Projecting downwardly on one side of the 75 bolt H is a serrated or notched leg, I, adapted to receive the end of the spring pawl or dog F.

The relation and proportions of the parts are such, as seen at Fig. 3 of the drawings, that the pawl or dog F, when in either of the 80 notches of the leg I, will bind the latter against the side of the cap-plate B and prevent the outward movement of the bolt until it shall have first been pushed inwardly sufficiently far to throw the dog into the position shown by 85 dotted lines 1, (see Fig. 3,) which movement would necessitate carrying the outward end of the seal-slot *f* within the forward end of the cap-plate B, and as the presence of the seal K would prevent such movement unless the same 90 was cut or removed, it is apparent that the bolt could not be moved into position to release the dog. When the seal has been cut and removed to allow the movement described, and the dog is thrown into the position shown by 95 dotted lines 1, the dog is pulled by the spring G to its normal position, and it will then lie behind the front end of the notched leg I, and the outward movement of the bolt H will cause the dog F to assume the position shown in dotted lines 2, allowing the bolt to be drawn sufficiently far forward to bring the gateway *g* 100

outside the cap-plate or case B, ready to receive a new seal. The bolt H is prevented from escaping entirely from the case by reason of the notched leg I coming in contact with the bolt-support D. I have shown the leg I with but two notches. I may make it with a greater number or with but a single one. I have found, however, that two are more desirable, as the clicking of the dog indicates the proper 10 point at which to cease the movement of the bolt.

The seals I use are composed of flat sheet metal, in one piece, with a shackle-like end adapted to enter the seal-slot f, and when the bolt is drawn out to its limit, so as to expose the gateway g, the shackle end of the seal is introduced and the bolt pushed back within its case until it assumes the position shown at Fig. 2, wherein, as will be observed, the seal is 15 locked against removal until the bolt is again drawn out to expose the gateway g, and as this movement cannot take place until the bolt has been forced still farther inwardly, it is obvious that the seal cannot be released, except 20 it be cut.

My improved catch is secured either in a horizontal or vertical position upon the door or door-jamb, and an ordinary hasp, L, secured in position to properly drop over the hasp-pro-

jection C on the plate A. When this has been 30 done the bolt H is drawn outwardly to cover and lock the hasp L in position, and the seal K put in place, and the bolt returned sufficiently far to prevent removal of said seal, but not far enough to uncover the hasp. It will 35 therefore be understood that before the hasp can be removed the seal, being made of one piece, must be cut, as heretofore described.

What I claim as new, and desire to secure by Letters Patent, is—

1. The combination of the plate A, provided with hasp-projection C, the sliding bolt H, provided with the slot f and gateway g, and the cap-plate B, substantially as described.
2. The combination and arrangement of the 45 plate A, cap B, sliding bolt H, with notched leg I, and the spring-dog F, substantially as and for the purpose described.

3. The T-shaped bolt H, having the rib provided with the longitudinal seal-slot f and 50 gateway g, substantially as described.

In testimony whereof I have hereunto set my hand and seal in the presence of two subscribing witnesses.

HENRY CLARKE. [L. S.]
